(57) **CLAIM**

The ornamental design for a set of components for a mobile communications device protective case, as shown and described.

DESCRIPTION

FIG. 1 is a front perspective view of the back plate component of a set of components for a mobile communications device protective case showing our new design;

FIG. 2 is a front view thereof;

FIG. 3 is rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of the face plate component of the set of components for a mobile communications device protective case;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof; and,

FIG. 15 is an exploded perspective view of both the face plate and back plate components of the set of components for a mobile communications device protective case.

The stippling on the drawing figures designates claimed subject matter and distinguishes between surfaces, which are stippled, and openings, which are not stippled.
